UNITED STATES PATENT OFFICE.

ALBERT F. FYANS, OF FALL RIVER, MASSACHUSETTS, ASSIGNOR TO FYANS RESEARCH CO., A FIRM COMPOSED OF A. F. FYANS, RICHARD BOARDMAN, AND JOHN T. FYANS, OF FALL RIVER, MASSACHUSETTS.

TOP-ROLL-SADDLE MECHANISM.

Original application filed April 18, 1927, Serial No. 184,487. Divided and this application filed September 17, 1927. Serial No. 220,133.

This invention relates to top roll mechanism and it has for its particular object to provide novel means for increasing the weight on the top roll saddle.

5 In top roll saddle mechanism, the weight is applied to the top saddle through the medium of a stirrup which is hung from the saddle and which is connected at its lower end to a weighted lever. Sometimes it is desirable to add more weight to the top roll, or to the top saddle, and one method by which this is sometimes accomplished is by adjusting the fulcrum point of the stirrup on the weighted lever.

15 My present invention, however, provides for adding to the weight on the top roll by employing a novel auxiliary weight, which may be readily applied to the usual weight that is hung from the weighted lever. In order to give an understanding of the invention, I have illustrated in the drawings a selected embodiment thereof, which will now be described, after which the novel features will be pointed out in the appended 25 claim.

The drawings show a top roll mechanism embodying my invention.

In the drawing 1 indicates the usual roller stand, which may be of any desirable con-

30 struction, and 2, 3 and 4 indicate the front, middle and rear bottom rolls, while 5, 6 and 7 indicate the front, middle and rear top rolls. The top roll saddle herein shown comprises the two saddle members 8 and 9. The 35 desired weight is applied to the saddle in usual manner through a stirrup 10 which is hung from the front saddle member 8 and is connected in usual manner at its lower end to the weighted lever 11. This lever is ful- 40 erumed at one end on the fulcrum member 12 and at its outer end it has a weight 13 applied thereto through the medium of the suspender 14.

The parts thus far described are, or may 45 be, all as usual in top roll saddle mechanism and form no part of my present invention.

As stated above, it is sometimes desirable to increase the weight on the top roll saddle.

My present invention provides for this by the employment of an auxiliary weight 15 which has a general bell-shape with an opening 16 in the top. The interior of the auxiliary weight 15 is of a size to receive the weight 13, so that the auxiliary weight can be hung on the weight 13 if added weight 55 is desired.

Whenever it is necessary for any reason to increase the weight on the top roll saddle, the weight 13 may be removed from the suspender 14 and the auxiliary weight may then 60 be slipped over the weight 13, after which said weight 13 with the auxiliary weight 15 thereon may be hung back on the suspender 14. The weight 12 is formed with a neck 17 which extends up through the opening 16 65 in the auxiliary weight, so that the opening through the neck which receives the hook 18 on the lower end of the suspender 14 is situated above the auxiliary weight. With this arrangement the presence of the auxiliary weight does not interfere with applying the weight 13 to the hook 14 or removing it therefrom. These auxiliary weights 70 15 can be inexpensively made and the invention thus provides a simple and inexpensive 75 means to secure added weight on any top roll.

This application is a division of my application Serial No. 184,487, filed April 18, 1927 which has matured into Patent No. 80 1,660,550, February 28th, 1928.

I claim:

In a drawing mechanism, drawing rolls, means to apply a weight thereto comprising a top saddle, a lever connected to said top saddle, and a main weight having a stem by which it is hung on the lever, in combination with a bell-shaped additional weight removably carried by the main weight and provided with an opening through which the stem extends and which may be applied to the main weight when additional weight 85 is required.

In testimony whereof, I have signed my name to this specification.

ALBERT F. FYANS.
